UNITED STATES PATENT OFFICE.

JOHN J. GAYNOR, OF INDIANAPOLIS, INDIANA, ASSIGNOR TO MEIER-GAYNOR MANUFACTURING CO., OF INDIANAPOLIS, INDIANA, A CORPORATION OF INDIANA.

BOTTLE-CROWNER.

1,381,628.

Specification of Letters Patent. Patented June 14, 1921.

Application filed July 5, 1919. Serial No. 308,807.

To all whom it may concern:

Be it known that I, JOHN J. GAYNOR, a citizen of the United States, residing at Indianapolis, in the county of Marion and State of Indiana, have invented a new and useful Bottle-Crowner, of which the following is a specification.

It is the object of my invention to provide a simple feed device for feeding bottle crowns to a crowning mechanism, and to prevent the feeding of a crown to such mechanism when the one previously fed thereto has not been used.

The accompanying drawings illustrate my invention: Figure 1 is a perspective view of a crowner embodying my invention; Fig. 2 is a vertical section through such a crowner, taken substantially on the line 2—2 of Fig. 4; Fig. 3 is an enlarged fragmentary vertical section through the lower end of the crowning head and the lower end of the feed chute; Fig. 4 is a section on the line 4—4 of Fig. 2; Fig. 5 is a fragmentary horizontal section on substantially the same line as Fig. 4, showing on a larger scale the crowning head and the discharge end of the feed chute; and Fig. 6 is a vertical section through the lower end of the feed chute, showing the crown-supporting ring of the crowning head as it approaches said feed chute.

A bottle-supporting table 10 is carried by a pedestal 11 suitably supported on a base 12. Three vertical shafts 13, 14, and 15 project through this bottle-carrying table 10, and below such table are provided with intermeshing gears 16, 17, and 18 respectively, which gears mesh to drive the shafts 13 and 15 in the same direction and the shaft 14 in the opposite direction, the shaft 15 rotating at twice the speed of the shaft 14 in the arrangement shown. The shaft 13 is connected by bevel gearing 19 to a horizontal driving shaft 20 mounted in the pedestal 11 and driven in any convenient manner.

The shafts 13 and 15 are provided with bottle-carrying disks 25 and 26, the upper surfaces of which are flush with the upper surface of the table 10; the disk 26 is a heavy disk, as it carries the bottle during

the crowning operation, and is preferably provided with a hard rubber plate 27 set in its upper surface on which plate the bottle stands while it is being crowned. The shaft 14 is provided above the table 10 with a transverse member 28, of any suitable shape, for engaging the bottle on its side and carrying it from the disk 25 to the disk 26 over the surface of the table 10. The bottles are guided in their travel by suitable fixed partitions 31, 32, and 33, shown in plan in Fig. 4. The bottles are fed on to the table 10 in any suitable way between the partitions 31 and 32, and guided thereby on to the disk 25; which carries them in a counterclockwise direction into position to be engaged in a notch 34 on the transverse member 28; which member in turn slides the bottles onward over the table 10 in a clockwise direction about the shaft 14 and on to the disk 26, the bottles being guided by being in constant engagement with the guiding partition 32; and the disk 26 carries the bottles in a counterclockwise direction while the crowning operation takes place, and delivers them crowned on to the table 10 and into a pocket formed by the partition 33, the two ends of which project over the disk 26 to guide the bottles into such pocket.

The travel of the bottles on the disk 25 is controlled by a stop 40, which is suitably operated, as explained in my co-pending application Ser. No. 308,806, so that a bottle is released in proper time to be carried onward by the disk 25 into engagement with the notch 34.

A chute 30 is supplied with bottle crowns from a hopper 50, from which the crowns are fed to the chute by any suitable mechanism operated by a pulley 51 driven by a belt 52 from a pulley 53 on one end of a horizontal shaft connected by bevel gearing 54 to the upper end of the vertical shaft 15. The upper end of the chute 30 may be nearly or quite vertical, and the crowns therein are in line one above the other, and rest upon one another, as is clear from Figs. 1, 2, and 3. The lower end of the chute, however, is curved so that its free end is substantially horizontal, so that the crowns at such free end

end will lie horizontal with their open side downward. This lower curved end of the chute 30 is formed by a section 55, which is pivoted to the main body of the chute on a pivot pin 56 so that its free end may swing upward or downward as required. The downward movement of the pivoted section 55 of the chute is limited by a pin-and-slot connection 57 between such pivoted section 10 and a depending arm 58 from a small cam 59, which is carried by depending arms 60 from a main or large cam 61 from which the lower end of the fixed portion of the chute 30 may also be supported. The pivoted section 55 of the chute is spring-pressed downward by a spring 62, and is provided with an end wall 63 which limits the movement of the crowns in the chute; and has a lateral arc-shaped chute-extension 64, the center of curvature of which is the axis of the shaft 15. This extension 64 is provided by a floor and side walls only, being open at the top, and a spring finger 65 projects obliquely downward through the open top to 20 prevent the end crown in the chute from being moved along such lateral extension until it is positively pushed therealong, as is clear from Figs. 5 and 6. The floor of the chute extension 64 is provided with a medial arc-shaped slot 66, also having the axis of the shaft 15 for its center of curvature. This slot permits a pin 67 carried by a 25 crown-supporting ring 68 to engage the edge of the end crown in the chute to force such crown out along said chute-extension 64 as the ring 68, which is carried eccentrically on and rotates with the shaft 15 in vertical alinement with the bottle to be crowned, travels during such shaft movement. When 30 the pin 67 has carried the crown to the end of the chute extension 64, such crown drops on to such ring 68. Such ring has a vertical hole through it, with its point of smallest diameter below its upper surface, as is clear 35 from Figs. 2, 3, and 6. This smallest diameter is too small to permit an uncrimped crown to pass through, so that when a crown drops on to the ring 68 it rests thereupon in the funnel-shaped part of said hole above 40 such point of smallest diameter; but this smallest diameter is sufficiently large to permit the mouth and neck of a bottle to pass through it, and also to permit a crimped crown on the mouth of such bottle to pass 45 through it.

Sometimes, however, the ring 68 already has a crown upon it when it approaches the crown-chute, and then it is desired that it should not receive another crown from the chute. Therefore, the pivoted section 55 of the chute is provided with a pair of lifting cams 69 which project laterally from it near its free end in the direction from which the rings 68 approaches it, these two lifting cams being separated to act evenly on the

crown on such ring and to allow the pin 67 to pass between them and being curved to conform to the line of travel of such pin, as is clear from Fig. 5. If the ring 68 as it approaches the crown chute has a crown 70 upon it, as indicated in Fig. 6, such crown engages the two lifting cams 69, and lifts such cams and the pivoted section 55 upward to swing the pivoted section 55 about its pivot pin 56 so that the end crown in the chute will be out of the path of the pin 67 and of the crown on the ring 68 so that such ring will pass beneath the end of the crown chute without removing a crown therefrom. When the ring 68 has passed from beneath 80 the chute extension 64, the pivoted section drops to its lower position, determined by the pin-and-slot connection 57. This lifting of the pivoted section 55 only occurs when the ring 68 is carrying a crown as it approaches the crown chute.

The shaft 15 also carries the crowning mechanism, for clamping on the mouth of the bottle the crown resting on the ring 68. This crowning mechanism, the shaft 15, the 90 disk 26, a pushing finger carried by the shaft 15 to engage the side of the bottle on such disk to hold it in proper position, the bottle, and the ring 68 all rotate together, with the bottle in vertical alinement with 95 the crowning mechanism and the ring 68, and the crowning operation takes place as they move. The details of the crowning mechanism, *per se*, form the subject-matter of my co-pending application Ser. No. 100 308,806, of even filing date herewith.

This crowning mechanism comprises a vertically movable crowning head 75, which is carried by a sleeve 76 splined on the shaft 15, which sleeve also has fixed thereon the 105 crown-supporting ring 68. This crowning head is provided with a lifting roller 77 which cooperates with the main lifting cam 61 to raise the sleeve and the parts carried thereby during one part of the rotation of 110 the shaft 15, and with a depressing roller 79 which at one point of the rotation of the shaft 15—the point of maximum compression and the low point of the cam 61—passes beneath a roller 80 on the end of a pivoted 115 arm 81 spring-pressed downward by an adjustable spring 82. The head 75 is provided at its lower end with a movable throat member 83 having a cone-shaped throat or opening therethrough, which throat during the 120 crowning operation engages the corrugated edge of the crown on the bottle mouth and crimps such edge inward beneath the bead at the bottle mouth. Within this crowning head 75 there is a compressing plunger 84, 125 which is spring-pressed downward within such head by a spring 85 but may be pushed upward within such head. The upward movement of the plunger 84 within the head is limited by the engagements of a collar 86 130

on the plunger and a shoulder 87 on the interior of the crowning head upon a predetermined relative movement between them, so that when such parts are in engagement 5 the continued downward movement of the crowning head produces a positive downward action on the plunger. The plunger 84 has a laterally projecting pin on which is mounted a roller 88, which co-operates with 10 the small cam 59 to raise the plunger 84 within the head 75 as the latter passes over the end of the pivoted section 55 of the chute, for such end lies close to the shaft 15 so that it passes between such head and the 15 ring 68 as such parts move in the rotation of the shaft 15. The cam 59 is properly shaped to produce this lifting action on the plunger 84, for clearance between the chute and the plunger. 20 The bottle to be crowned is carried on by the shoulder 34 on to the disk 26 at the proper time to be received on the hard rubber plate 27 and in vertical alinement with the ring 68 and the plunger 84, and is carried forward in such position by the rotation 25 of the disk and the pushing action of the finger 70. The bottle reaches this position about at the time the ring 68 is passing out from beneath the chute-extension 64, as is 30 clear from Fig. 4, so that the ring 68 has upon it a crown which it received from the chute as it passed thereunder in the last or some preceding revolution. At this time the crowning head is at substantially its highest 35 point, by the interaction of the cam 61 and lifting roller 77. As the shaft 15 continues to rotate, the crowning head 75 is started on its downward movement, the ring 68 and all the parts carried by the sleeve 63 moving 40 with it. As these parts move downward, the bottle remaining vertically stationary on the disk 26, the ring 68 passes down around the mouth of the bottle, and such mouth lifts from the descending ring the crown which 45 the latter is carrying, while the ring goes on downward on the bottle neck toward the dotted line position shown in Fig. 2. As the mouth of the bottle thus receives its crown, the action of the small cam 59 and the descending movement of the sleeve 63 and the parts carried thereby bring the plunger 84 into engagement with the top of the crown; and as the head 75 continues to descend, the plunger 84 is pushed relatively upward with 50 in the crowning head and the conical throat in such head engages and crimps inward the edge of the crown around the bead on the bottle mouth, while the downward pressure of the plunger compresses the cork lining of the 55 crown. This downward pressure at the last is a positive pressure, by reason of the engagement of the collar 86 and shoulder 87, so that a positive compressing action of the crowning head on the cork lining of the 60 crown is obtained. This makes an air-tight closure of the bottle, which is maintained permanent by the locking action of the crimped edge of the crown around the bead at the bottle mouth. The final compressing and crimping action occurs as the roller 79 70 passes beneath the roller 80, as indicated in dotted lines in Fig. 2, and the degree of compression of the cork lining is controlled by the adjustment of the spring 82. The roller 77 separates from the cam 61 during this 75 final action, to allow the free action of the spring 82. After the crowning is complete, the cam 61 again engages the roller 77 to lift the head 75 and with it the sleeve 63 and the ring 68, so that the crowning head and the 80 compressing plunger are separated from the crowned bottle and the ring 68 is removed from around the neck of the bottle, the crimped crown on the bottle passing freely through the opening in such ring. The 85 crowned bottle is carried by the rotating disk 26 into the opening between the ends of the partition 33, and delivered into the pocket for the crowned bottles, which may be removed from such pocket as desired. 90

The normally stationary parts, such as the cam 61, the hopper 50, and the chute 30, are vertically adjustable for different heights of bottles. To this end, they are all carried by a vertically adjustable frame 90, which is 95 provided with two sleeves 91 vertically slidable on two vertical screws 92, on which there are hand-wheel nuts 93 engaging such sleeves 91 at top and bottom to produce such vertical adjustment. The bevel gearing 54. 100 is also carried by this frame 90, and on account of this vertical adjustment that bevel gear of such gearing which is on the shaft 15 is splined on such shaft. By manipulating the nuts 93, the apparatus may be adjusted 105 for any desired height of bottle. This is the only adjustment required, as the vertical adjustment of the cam 78 determines the height at which the crowning head operates. 110

By the term "bottle" I intend to include any suitable container, and not to limit myself to containers with necks and mouths smaller than their bodies; and by the term "crown" I intend to include other covering and capping devices than those with corrugated edges. 115

I claim as my invention:

1. In a crowner, the combination of a crown chute having a movable discharge end, crowning mechanism movable past said chute, said crowning mechanism being provided with crown-supporting means arranged to remove a crown from said chute as it passes thereby, and means on said chute for co-operating with a crown on said crown-supporting means if the latter bears a crown as it approaches said chute for moving the discharge end of the chute out of position to have a crown removed from it by said crown-supporting means. 120
2. In a crowner, the combination of a crown chute having a movable discharge end, crowning mechanism movable past said chute, said crowning mechanism being provided with crown-supporting means arranged to remove a crown from said chute as it passes thereby, and means on said chute for co-operating with a crown on said crown-supporting means if the latter bears a crown as it approaches said chute for moving the discharge end of the chute out of position to have a crown removed from it by said crown-supporting means. 125
3. In a crowner, the combination of a crown chute having a movable discharge end, crowning mechanism movable past said chute, said crowning mechanism being provided with crown-supporting means arranged to remove a crown from said chute as it passes thereby, and means on said chute for co-operating with a crown on said crown-supporting means if the latter bears a crown as it approaches said chute for moving the discharge end of the chute out of position to have a crown removed from it by said crown-supporting means. 130

2. In a crowner, the combination of a crown chute having at its discharge end a pivoted section in the discharge end of which a crown lies horizontal, said pivoted section being arranged to have a vertical swinging movement and being provided with a lateral discharge outlet, a rotating shaft carrying a crowning head and a crown-supporting ring in alinement with each other and arranged by the rotation of the shaft to pass respectively above and below the discharge end of said chute, means on said ring for removing a crown from the lateral discharge opening of said chute as the ring passes beneath the chute, and means on said chute for coöperation with a crown on the ring if the latter carries a crown as it approaches the chute for lifting said pivoted end portion of the chute out of position to have a crown removed from it by the ring passing beneath it.

3. In a crowner, the combination of a crown chute having at its discharge end a pivoted section in the discharge end of which a crown lies horizontal, said pivoted section being arranged to have a vertical swinging movement and being provided with a lateral discharge outlet, a rotating shaft carrying a crown-supporting member arranged to pass beneath the discharge end of said chute as the shaft rotates, said crown-supporting member being provided with an upwardly projecting finger arranged to engage a crown in said chute and to remove it through said lateral opening on to said crown-supporting member as the latter passes beneath said chute, a spring retaining-finger for holding against accidental removal from said chute the crown which is in readiness for removal, and a cam projecting from said pivoted section on the side from which the crown-supporting member approaches it for engaging a crown on said member and lifting said pivoted section so that the end crown therein will be out of the path of said pin if said member has a crown upon it as it approaches said chute.

4. In a crowner, the combination of a crown chute having at its discharge end a pivoted section in the discharge end of which a crown lies horizontal, said pivoted section being arranged to have a vertical swinging movement and being provided with a lateral discharge outlet, a rotating shaft carrying a crown-supporting member arranged to pass beneath the discharge end of said chute as the shaft rotates, said crown-supporting member being provided with an upwardly projecting finger arranged to engage a crown in said chute and to remove it through said lateral opening on to said crown-supporting member as the latter passes beneath said chute, and a cam projecting from said pivoted section

on the side from which the crown-supporting member approaches it for engaging a crown on said member and lifting said pivoted section so that the end crown therein will be out of the path of said pin if said member has a crown upon it as it approaches said chute.

5. In a crowner, the combination of a crown chute having at its discharge end a pivoted section in the discharge end of which a crown lies horizontal, said pivoted section being arranged to have a vertical swinging movement and being provided with a lateral discharge outlet, a rotating shaft carrying a crown-supporting member arranged to pass beneath the discharge end of said chute as the shaft rotates, said crown-supporting member being provided with an upwardly projecting finger arranged to engage a crown in said chute and to remove it through said lateral opening on to said crown-supporting member as the latter passes beneath said chute, a spring retaining-finger for holding against accidental removal from said chute the crown which is in readiness for removal, and a pair of cams projecting from said pivoted section on the side from which the crown-supporting member approaches it and lying on opposite sides of the path of said pin for engaging a crown on said member and lifting said pivoted section so that the end crown therein will be out of the path of said pin if said member has a crown upon it as it approaches said chute.

6. In a crowner, the combination of a crown chute having at its discharge end a pivoted section in the discharge end of which a crown lies horizontal, said pivoted section being arranged to have a vertical swinging movement and being provided with a lateral discharge outlet, a rotating shaft carrying a crown-supporting member arranged to pass beneath the discharge end of said chute as the shaft rotates, said crown-supporting member being provided with an upwardly projecting finger arranged to engage a crown in said chute and to remove it through said lateral opening on to said crown-supporting member as the latter passes beneath said chute, and a pair of cams projecting from said pivoted section on the side from which the crown-supporting member approaches it and lying on opposite sides of the path of said pin for engaging a crown on said member and lifting said pivoted section so that the end crown therein will be out of the path of said pin if said member has a crown upon it as it approaches said chute.

7. In a crowner, the combination of a crown chute, a vertical rotating shaft, a sleeve rotatable with said shaft but movable longitudinally thereon, a crowning head and a crown-supporting member mounted

- on said sleeve and partaking of the movements thereof and spaced apart vertically so that as the shaft rotates they pass respectively above and below the discharge end 5 of said chute, said crown-supporting member being arranged to receive crowns from said chute as said shaft rotates and said crown-supporting member passes beneath the discharge end of said chute, means on 10 said shaft for supporting a bottle to be crowned, and means for moving said sleeve longitudinally of the shaft as the latter rotates to cause said crown-supporting member to deposit its crown on the mouth of the 15 bottle and said crowning head to fasten such deposited crown to the bottle.
8. In a crowner, the combination of a crown-supplying chute, a rotating shaft, a crowning head and a crown-supporting member carried by said shaft and rotatable therewith and spaced apart vertically so that as the shaft rotates they pass respectively above and below the discharge end of said chute, a bottle-supporting member also carried by said shaft and rotatable therewith, said crown-supporting member being arranged to receive a crown from said chute as said shaft rotates and said crown-supporting member passes under the discharge end 25 of said chute, and means for producing a relative movement between said bottle-supporting member and said crowning head and crown-supporting member as the shaft rotates for causing the crown-supporting member to deposit its crown on the mouth of a bottle on said bottle-supporting member and such crowning head to fasten such crown to the bottle.
9. In a crowner, the combination of a 30 crown chute, a rotatable shaft carrying a crowning head and a crown-supporting member which are rotatable with the shaft but longitudinally movable thereon and spaced apart vertically so that as the shaft rotates they pass respectively above and below the discharge end of said chute, and stationary camming means for moving said crowning head and said crown-supporting means so that as they pass the chute the 35 crowning head passes above and clears the chute and the crown-supporting member passes below said chute.
10. In a crowner, the combination of a 40 crown chute, a rotatable shaft carrying a crowning head and a crown-supporting member which are rotatable with the shaft but longitudinally movable thereon, and stationary camming means for moving said crowning head and said crown-supporting 45 means so that as they pass the chute the crowning head passes above and clears the chute and the crown-supporting member passes below said chute, the discharge end portion of said chute being vertically movable, means on said crown-supporting mem- 50 ber for removing a crown from said chute as it passes thereunder, and means operated by the presence of a crown on said crown-supporting member as the latter approaches said chute for lifting the end section of said 55 chute so that the crown therein in readiness for removal is out of the path of said crown-removing means.
11. In a crowner, the combination of a 60 crown chute having a discharge end in which a crown lies horizontal, a rotating shaft, a crowning head and a crown-supporting member rotatable with said shaft and spaced apart vertically so that as the shaft rotates they pass respectively above and below the 65 discharge end of said chute, said crowning head including a throat member for crimping the edge of the crown and a compressing plunger for engaging the top of the crown and pressing it on the bottle mouth, 70 said throat member and said plunger being relatively movable, said parts being arranged so that as the shaft rotates said chute passes between the crowning head and the crown-supporting member, and a cam for co-operating with said plunger for lifting it as it passes said chute so that it will clear the latter.
12. In a crowner, the combination of a 75 crown chute having a discharge end in which a crown lies horizontal, a crown-supporting member movable transversely of the chute beneath the crown in the end of said chute, said chute being provided with a lateral discharge opening at its discharge end, and means on said crown-supporting member for removing a crown from said discharge opening and letting it drop on said member as 80 said member passes said chute.
13. In a crowner, the combination of a 85 crown chute in the discharge end of which a crown lies horizontal, said chute being provided with a lateral discharge outlet, a rotating shaft carrying a crowning head and a crown-supporting ring in alinement with each other and arranged by the rotation of the shaft to pass respectively above and below the discharge end of said chute, and means on said ring for removing a crown 90 from the lateral discharge opening of said 95 chute as the ring passes beneath the chute.
14. In a crowner, the combination of a 100 crown chute in the discharge end of which a crown lies horizontal, said chute being provided with a lateral discharge outlet, and a rotating shaft carrying a crown-supporting member which by the rotation of the shaft 105 passes beneath a crown in the discharge end of said chute and removes such crown therefrom.
15. In a crowner, the combination of a 110 crown chute in the discharge end of which a crown lies horizontal, said chute being provided with a lateral discharge outlet, a rotating shaft carrying a crown-supporting 115 member which by the rotation of the shaft passes beneath a crown in the discharge end of said chute and removes such crown therefrom.

member which by the rotation of the shaft passes beneath a crown in the discharge end of said chute and removes such crown therefrom, and a crowning head and a bottle-supporting member arranged to coöperate with said crown-supporting member to transfer to the mouth of a bottle a crown on said

crown-supporting member and fasten such crown to the bottle.

In witness whereof, I have hereunto set my hand at Indianapolis, Indiana, this 19th day of June, A. D. one thousand nine hundred and nineteen.

JOHN J. GAYNOR.
